United States Patent Office.

FREDERICK W. BROCKSIEPER, OF NEW HAVEN, CONNECTICUT, ASSIGNOR
TO SARGENT & CO., OF SAME PLACE.

Design No. 4,467, dated November 15, 1870.

DESIGN FOR A LOCK-FRONT.

The Schedule referred to in these Letters Patent and making part of the same.

To all whom it may concern:

Be it known that I, FREDERICK W. BROCKSIEPER, of New Haven, in the county of New Haven and State of Connecticut, have invented a new Design for Lock-Front; and I do hereby declare the following, when taken in connection with the accompanying drawing and the letters of reference marked thereon, to be a full, clear, and exact description of the same, and which said drawing constitutes part of this specification, and represents, in—

Figure 1, a front view; and in
Figure 2, a transverse section.

This invention relates to a design for the front of locks or latches, commonly called lock-fronts; and consists in the ornamentation of the front by extending a sunken beading around the plate, near the edge, as fully shown in the accompanying drawing.

The front as here represented is constructed with

a single bolt-opening, A, and screw-holes a at each end.

Around the front, near the edge, is formed a sunken beading, d, as seen in figs. 1 and 2.

In addition to this ornamentation a similar transverse beading may be made above and below the bolt-opening, and around the screw-holes, and other ornamentation within the beading may be sunk in similar manner, my invention being the design of the sunken beading around the plate, near its edge, with or without the ornamentation within the said beading.

I claim as my invention—

The design for lock-front, as described and shown in the accompanying illustration.

F. W. BROCKSIEPER.
